Int. Cl. D7—06

U.S. Cl. D49—8.2

The characteristic features of my design reside in the surface patterns shown, in combination with the bow.

This application is a continuation-in-part of my co-pending application Ser. No. D. 8,700 filed Sept. 22, 1967 and now abandoned.

I claim:

The ornamental design for a cover for a clothes hamper, substantially as shown and described.
